UNITED STATES PATENT OFFICE.

SAMUEL A. HELFGOTT, OF BROOKLYN, NEW YORK.

GAME.

Application filed August 6, 1927. Serial No. 211,057.

This invention is a game adapted to be played upon a playing board similar in some respects to a checker board, but embodying an entirely different number of spaces and 5 with more spaces in one direction than the other.

The object of the invention is to provide a simple and compact construction on which the game of baseball can be figuratively 10 played and to provide a game which will constitute a pleasant and interesting pastime.

The board on which the game is played is laid off in alternate squares of contrasting colors, said board being rectangular in contour. There are nine rows of squares extending longitudinally of the board and more than nine rows of squares, preferably 15 twelve, extending transversely of the board. One end of the board is designated "At bat"

20 and the other end of the board "At field" and the four rows of squares next adjacent the "At field" end of the board are designated "Runs", "Third base", "Second base", "First base", with "Runs" between "At field" and 25 "Third base", and "Third base" between "Runs" and "Second base", and "Second base" between "Third base" and "First base" and "First base" between "Second base" and award row. Arrows may be associated with 30 these legends to more clearly designate the rows in question. The next adjacent transverse row may be referred to as the award row, since upon the spaces thereof are designated such legends as "Base on errors", 35 "Single", "Triple", "Home run", etc., although one or more of these spaces may be marked to constitute a penalty or "Out". This award row is next adjacent the first base row of squares.

40 Throughout the surface of the board, certain spaces are furthermore marked to signify penalties, e. g. "Out" or "Out on fly", or other appropriate terminology used in baseball language.

45 The game is played with eighteen checks or "men" which may, if desired, be of the same character as are used in playing checkers, pachisi or the like and they are moved over the board in a manner herein- 50 after more fully described.

Features of the invention, other than those specified, will be apparent from the herein-

after detailed description and claims, when read in conjunction with the accompanying drawing.

55 The accompanying drawing illustrates one practical embodiment of the invention, but the construction therein shown is to be understood as illustrative, only, and not as defining the limits of the invention.

60 The drawing shows the game of the present invention slightly in perspective.

The drawing shows a game board of substantially rectangular contour. The central portion of the board is laid out with a series 65 of squares, there being 12 transverse rows of squares designated by the reference characters 1, 2, 3, 4, 5, 6, 7, 8, 9, 10, 11 and 12 and nine longitudinal rows of squares designated 70 13, 14, 15, 16, 17, 18, 19, 20 and 21 respectively.

The transversely extending rows are shown as twelve in number as this mathematically works out the best with relation to the moves involved in the playing of the 75 game, although a greater or lesser number of transverse rows may be employed. This number is, however, preferably more than nine in order that a proper defense may be set up by the defending team as will herein- 80 after be apparent. The squares of the several rows are alternately of contrasting colors and, in practice, these alternate squares may, for example, be black and white. At one end of the board adjacent 85 the transverse row 1, is the legend "At bat" and at the other end of the board and similarly placed, and adjacent the transverse row 12, is the legend "At field".

90 A line of spaces 12 which is directly adjacent the latter legend is designated along opposite lateral sides of the board by the legends "Runs". Similarly, the rows 11, 10 and 9 are designated "Third base", "Second base" and "First base", respectively. Arrows 95 22 and 22' preferably in colors contrasting to the surface of the board are employed in conjunction with these legends and point to the rows of spaces to which the legends refer. Opposite the row 2 are similar arrows 23 and 23' on which are contained the legend "Play ball". It will be noted 100 that the legends on the arrows 22 and 23 are readable from the "At bat" end of the board,

while the legends on the arrows 22' and 23' are readable from the "At field" end of the board.

The row designated 8, which is adjacent 5 first base, is the so-called award row. The spaces of this row bear legends such as "Base on errors", "Single", "Triple", "Home run", "Double", etc. A suitable picture such 10 as the representation of a baseball may also be shown upon these spaces. Other spaces through the board bear legends appropriate 15 to penalties, such as "Out on fly", "Out on sacrifice" and the like. These spaces may contain a suitable picture such as the representation 20 of cross bats as shown. Moreover additional spaces of the rows 3 to 7 inclusive bear the legends "Balls" and "Strikes," respectively. All of these legends are duplicated in reversed relation so as to be readable

25 from the both sides of the board.

The directions for playing the game are 30 preferably printed at the right and left sides of the board as noted in reverse direction so that they can be read respectively 35 from the opposite ends of the board.

In playing the game, 18 checks or "men" 35 are employed as there are nine players on a "side" in baseball. The checks X are appropriate to the team at bat and the checks Y 40 are appropriate to the team in the field. The nine men X at bat line up in the row 1 adjacent legend "At bat" with one man on each square and the men at field Y line up at the other end of the board in the row 12 adjacent the legend "At field", so that the two 45 end rows 1 and 12 each contain one man per square.

The men X at bat start the game by moving a man X one square forwardly in a diagonal direction as in checkers and the men Y 50 at field respond in the same manner. The team at bat or team at field can bring more than one man into play at any time thereafter. The moves of the respective sides or 55 teams being alternate as the inning is continued. Each player of the game has the option as to which man shall be played so that the players of the game stand in substantially the same position as the manager 60 of a team on the players' bench in the game of baseball. In other words, the men are moved in accordance with the carefully thought out plan of the manager-players.

The men at field may occupy any square, 65 but men at bat can occupy safe squares only and should this man or men enter other squares (designated by cross bats) they are to be removed from board. Jumping or skipping is obligatory and all men skipped or 70 jumped shall also be removed from board as in checkers. When three men of team at bat are removed from board, it constitutes 75 3 "Outs." The board is re-set and opposing team goes to bat. The game is thus continued for nine innings or more if necessary,

as in baseball. When in the process of jumping or skipping more than one man, should man at bat encounter a penalty square (marked by cross bats), he ceases jumping or skipping and is removed from 70 the board. Removing man from board does not constitute a move.

When men at bat enter award squares 75 entitling them to one or more bases they cannot be jumped or skipped, but shall be placed on any safe square on corresponding base. If any space of the appropriate base or other 80 is already occupied, the man or men thereon advance accordingly. Placing of men on appropriate bases does not constitute a move. More than one man cannot occupy any one 85 of the bases at the same time, any more than they can in the game of baseball as played on the diamond.

Men on bases advance one base when man 90 at bat enters square marked "Out on sacrifice" (marked by crossing of bats). If one of the men X, at bat, succeeds in occupying the space marked "Hit by pitched ball" in line 6, it is entitled to be placed at once on 95 "First base".

When any of the men at bat reach the row 100 of squares 12 marked "Runs", they shall be removed from board and counted as runs earned. The team having most runs after 95 nine innings of play or more if necessary is the winner of the game (as in baseball).

It will be apparent from the foregoing 105 description of the game and its operation that the purpose of the men in the field is to preclude the men at bat from entering the award spaces and it is in order to enable the team in the field to build up a proper defense for these spaces that the playing 110 spaces are of greater number longitudinally of the board than transversely thereof. If the playing zone were substantially square the team at bat would very easily advance a man to the award spaces before a proper defense could be built up, while with the arrangement shown I have found that the 115 chances for and against the making of runs are about even. It will be noted moreover that in order to score a run, the men at bat must travel to the extreme opposite end of the board and pass over first, second and third base stations as in the game of baseball.

The team in the field has every opportunity 120 to effect an "Out" from the time the player leaves home plate "At bat" until the man is actually moved into the run spaces. The present game therefor very closely simulates the game of baseball while affording ample 125 opportunity for the exercise of skill, thought and amusement. Moreover, as the game of baseball is understood by both old and young, the game is well adapted to be played by persons of all ages.

I have shown in the accompanying draw- 130

ing, the game in its preferred form, but inasmuch as the details may be changed without departing from the invention, the invention is to be understood as fully commensurate with the appended claims.

Having thus fully described the invention, what I claim as new and desire to secure by Letters Patent is:

1. A baseball game board, a portion of the face of which is divided into squares of alternately different colors there being nine rows of squares extending longitudinally of the board and upwardly of nine rows of squares extending transversely of the board, the transverse row of squares at one end of the board being suitably marked to designate men at bat and the transverse row at the opposite end of the board being suitably marked to designate men at field, legends for suitably marking transverse rows near the at field end of the board with designations appropriate to first, second and third base, award legends on certain squares and penalty legends on certain other squares, in combination with checks adapted to be placed on and moved over the squares of the board. 70
2. A baseball game board, a portion of the face of which is divided into squares of alternately different colors there being nine rows of squares extending longitudinally of the board and upwardly of nine rows of squares extending transversely of the board, a legend "At bat" adjacent the transverse row of squares at one side of the board, a legend "At field" adjacent the transverse row of squares at the opposite end of the board, legends "Third base," "Second base" and "First base," adjacent the second, third and fourth transverse rows of squares from the "At field" end of the board, award legends on certain squares of the board and penalty legends on certain other squares of the board, in combination with checks adapted to be placed on and moved over said squares. 75
3. A baseball game board, a portion of the face of which is divided into squares of alternately different colors there being nine rows of squares extending longitudinally of the board and upwardly of nine rows of squares extending transversely of the board, the transverse row of squares at one end of the board being suitably marked to designate men at bat and the transverse row at the opposite end of the board being suitably marked to designate men at field, legends for suitably marking transverse rows near the at field end of the board with designations appropriate to first, second and third base, said legends being duplicated at the opposite transverse sides of the board in reverse direction so that they can be respectively read from both ends of the board, award legends on certain squares and duplicated on each square in reverse relation to be respectively 80
4. A baseball game board, a portion of the face of which is divided into squares of alternately different colors there being nine rows of squares extending longitudinally of the board and twelve rows of squares extending transversely of the board, the transverse row of squares at one end of the board being suitably marked to designate men at bat and the transverse row at the opposite end of the board being suitably marked to designate men at field, legends for suitably marking transverse rows near the at field end of the board with designations appropriate to first, second and third base, award legends on certain squares and penalty legends on certain other squares, in combination with nine checks of one color adapted to be played as men at bat and nine checks 85
5. A baseball game board, a portion of the face of which is divided into squares of alternately different colors, there being nine rows of squares extending longitudinally of the board and at least nine rows extending transversely of the board, legends "At field" and "Runs" adjacent the first transverse row of squares at one side of the board, a legend "Third base" adjacent the next transverse row of squares, a legend "Second base" adjacent the next transverse row of squares, a legend "First base" adjacent the next transverse row of squares, award legends in the squares of the next transverse row of squares, and a legend "At bat" adjacent the last transverse row of squares at the opposite side of the board, and penalty legends on certain squares of the board, in combination with checks adapted to be placed on and moved over the squares of the board. 90
6. A baseball game board, a portion of the face of which is divided into squares of alternately different colors, there being nine rows of squares extending longitudinally of the board and at least nine rows extending transversely of the board, legends "At field" and "Runs" adjacent the first transverse row of squares at one side of the board, a legend "Third base" adjacent the next transverse row of squares, a legend "Second base" adjacent the next transverse row of squares, a legend "First base" adjacent the next transverse row of squares, award legends to the squares of the next transverse row of squares, said award legends being duplicated in reversed direction so as to be 105
7. A baseball game board, a portion of the face of which is divided into squares of alternately different colors, there being nine rows of squares extending longitudinally of the board and at least nine rows extending transversely of the board, legends "At field" and "Runs" adjacent the first transverse row of squares at one side of the board, a legend "Third base" adjacent the next transverse row of squares, a legend "Second base" adjacent the next transverse row of squares, a legend "First base" adjacent the next transverse row of squares, award legends to the squares of the next transverse row of squares, said award legends being 110
8. A baseball game board, a portion of the face of which is divided into squares of alternately different colors, there being nine rows of squares extending longitudinally of the board and at least nine rows extending transversely of the board, legends "At field" and "Runs" adjacent the first transverse row of squares at one side of the board, a legend "Third base" adjacent the next transverse row of squares, a legend "Second base" adjacent the next transverse row of squares, a legend "First base" adjacent the next transverse row of squares, award legends to the squares of the next transverse row of squares, said award legends being 115
9. A baseball game board, a portion of the face of which is divided into squares of alternately different colors, there being nine rows of squares extending longitudinally of the board and at least nine rows extending transversely of the board, legends "At field" and "Runs" adjacent the first transverse row of squares at one side of the board, a legend "Third base" adjacent the next transverse row of squares, a legend "Second base" adjacent the next transverse row of squares, a legend "First base" adjacent the next transverse row of squares, award legends to the squares of the next transverse row of squares, said award legends being 120
10. A baseball game board, a portion of the face of which is divided into squares of alternately different colors, there being nine rows of squares extending longitudinally of the board and at least nine rows extending transversely of the board, legends "At field" and "Runs" adjacent the first transverse row of squares at one side of the board, a legend "Third base" adjacent the next transverse row of squares, a legend "Second base" adjacent the next transverse row of squares, a legend "First base" adjacent the next transverse row of squares, award legends to the squares of the next transverse row of squares, said award legends being 125
11. A baseball game board, a portion of the face of which is divided into squares of alternately different colors, there being nine rows of squares extending longitudinally of the board and at least nine rows extending transversely of the board, legends "At field" and "Runs" adjacent the first transverse row of squares at one side of the board, a legend "Third base" adjacent the next transverse row of squares, a legend "Second base" adjacent the next transverse row of squares, a legend "First base" adjacent the next transverse row of squares, award legends to the squares of the next transverse row of squares, said award legends being 130

readable from opposite sides of the board, and a legend "At bat" adjacent the last transverse row of squares at the opposite side of the board, and penalty legends on certain squares, of the board, said penalty legends being duplicated in reversed direction so as to be readable from opposite sides of the board, in combination with checks adapted to be placed on and moved over the squares of the board.

7. A baseball game board, a portion of the face of which is divided into squares of alternately different colors, there being nine rows of squares extending longitudinally of the board and at least nine rows extending transversely of the board, legends "At field" and "Runs" adjacent the first transverse row of squares at one side of the board, a legend "Third base" adjacent the next transverse row of squares, a legend "Second base" adjacent the next transverse row of squares, a legend "First base" adjacent the next transverse row of squares, award legends in the squares of the next transverse row of squares, and a legend "At bat" adjacent the last transverse row of squares at the opposite side of the board, and penalty legends on certain squares of the board, a pictorial representation of a baseball on each award square and a pictorial representation of cross bats on each penalty square, in combination with checks adapted to be placed on and moved over the squares of the board.

8. A baseball game board, a portion of the face of which is divided into squares of alternately different colors, there being nine rows of squares extending longitudinally of the board and at least nine rows extending transversely of the board, legends "At field" and "Runs" adjacent the first transverse row of squares at one side of the board, a legend "Third base" adjacent the next transverse row of squares, a legend "Second base" adjacent the next transverse row of squares, a legend "First base" adjacent the

next transverse row of squares, award legends in the squares of the next transverse row of squares, and a legend "At bat" adjacent the last transverse row of squares at the opposite side of the board, penalty legends on certain squares of the board, strike legends on other square of the board, and ball legends on still other squares of the board, in combination with checks adapted to be placed on and moved over the squares of the board.

9. A baseball game board, a portion of the face of which is divided into squares of alternately different colors, there being nine rows of squares extending longitudinally of the board and at least nine rows extending transversely of the board, legends "At field" and "Runs" adjacent the first transverse row of squares at one side of the board, a legend "Third base" adjacent the next transverse row of squares, a legend "Second base" adjacent the next transverse row of squares, a legend "First base" adjacent the next transverse row of squares, award legends in the squares of the next transverse row of squares, and a legend "At bat" adjacent the last transverse row of squares at the opposite side of the board, penalty legends on certain squares of the board, strike legends on other squares of the board, and ball legends on still other squares of the board, and a legend "Play ball" designating the row of squares next adjacent the "At bat" row of squares, and directions for playing the game positioned on opposite lateral margins of the board, all of the legends and directions on the board, except "At bat" and "At field", being duplicated in reverse relation to permit them to be read from opposite sides of the board, in combination with checks adapted to be placed on and moved over the squares of the board.

In testimony whereof I have signed the foregoing specification.

SAMUEL A. HELFGOTT.
